UNITED STATES PATENT OFFICE

1,967,516

PAPER TRIMMER

Charles T. Ridgely, Springfield, Ohio

Application September 3, 1932, Serial No. 631,634

21 Claims. (Cl. 164—84)

This invention relates to improvements in paper trimmers, and has for its object to provide a hand-operated trimmer mounted on a straight edge or guide, constituting a track for use in cutting off unused parts of wall paper, and may be, in fact, used for cutting paper in other places and under other conditions.

It is particularly the object of this invention to provide, in connection with a straight edge, a gauge member adapted to move along the straight edge for the purpose of cutting paper underneath the straight edge and along one edge thereof, and be guided on the straight edge with the least possible resistance by means of a spring plate and a removable wiper and lubricator thereon.

It is a further object of this invention to provide, in connection with a gauge or traveling member, a cast-in or shrunk pivot pin around which there is a seat for supporting a spring for operating a suitable cutter carried by the trimmer.

It is also an object of this invention to provide an adjustable rotary cutter, and a rotary removable and adjustable wiper or cleaner and lubricator for the cutter, and an improved means for limiting the swinging movement of the cutter with relation to the traveling member under the action of the lift spring.

It is also an object of this invention to provide, in connection with a trimmer, a guide pin for guiding the movement of the cutter, and a specially formed spring-operated pin for limiting the swinging movement of the cutter under the influence of the spring around the pivot pin.

These and other advantages will appear from the following description taken in connection with the drawings.

Referring to the drawings:

Figure 1 is a side elevation of the apparatus looking in the direction of the cutting side of the straight edge or track.

Figure 2 is a top plan view of the apparatus as shown in Figure 1.

Figure 3 is a side elevation of the apparatus and a section of the straight edge, showing the manner in which the apparatus is supported on the straight edge. In this figure the cutting blade is elevated out of cutting position.

Figure 4 is a view similar to Figure 3 but with the blade-carrying arm in its extreme elevated position, due to the removal of the stop pin and the action of the spring around the pivot pin.

Figure 5 is a section on the line 5—5 of Figure 3.

Figure 6 is an enlarged top plan view of the

front end of the trimmer, as shown in Figure 2.

Figure 7 is a horizontal section showing the manner in which the cutter case is attached to the gauge member, the manner in which the guide plate is attached to the gauge member and 60 the manner in which the rotary wiper is supported in connection with the cutter.

This apparatus is composed essentially of four parts, a straight edge, which affords a trackway upon which there is mounted a gauge member 65 constituting the second part, a cutter case carried by the gauge member, and a rotating cutter carried by the cutter case.

When this apparatus is in place the straight edge 1, which may be of any desired or convenient length, is placed along the paper with the edge abutting the line along which the paper is to be trimmed or cut. On the straight edge, adjacent one edge thereof, is a groove 2; extending up the face of the track edge adjacent the groove, 75 and bent over to partly cover the groove is a straight edge track 3 of some suitable material, such as brass, or any other like material.

The metal trackway has a vertical part and a horizontal part. The horizontal part extends 80 over the groove in the straight edge. It is along the vertical part of the track that the cutter blade travels and is guided. Upon this trackway there is located, for longitudinal movement thereon, a gauge member or traveling member 4, 85 which has on one side thereof guides 5 to properly locate the traveling member with respect to the straight edge. These guides pass along the vertical part of the trackway when the gauge member moves along the straight edge. 90

On the side of the gauge member opposite the guides 5 are two bosses, a forward, relatively long boss 6 and a rear round boss 7. In the forward boss is a hole 8, the purpose of which will be later described. These bosses support a plate 9 which has extending from one edge thereof a flange 10, which is adapted to extend beneath one edge of the track 3. This plate is supported on the gauge member by means of two screws 11, extending into the forward boss 6, and a single screw 11, extending into the rear boss. 100

Between the plate and the gauge member and seated in the hole 8 is a relatively heavy spring 12. This spring, in cooperation with a spring 14 located in a hole 13 around the screw 11 in the rear boss, tends to hold the plate 9 against the heads of the screws 11. By means of these screws the plate 9 may be adjusted with relation to the track 3. The spring 12 is a heavier spring than the spring 14 and is located opposite the cutter, and 105

110 Figure 6 is an enlarged top plan view of the

sustains a greater pressure during the operation of the trimmer.

Supported on the plate 9, between the two bosses, is a wiper 15. This wiper extends laterally and is adapted to engage the under side of the trackway to remove any grit or foreign material that may accumulate thereon, and to lubricate the track so that the trimmer will easily travel. Extending upwardly from this wiper or oiler plate 15 is a bracket 16, by means of which the wiper plate is attached to the plate 9 through a screw 17.

On the upper side of the plate 15 is a felt or fibrous wiping material 18. The plate with the wiping material thereon may be removed from the plate 9 by removing the screw 17. Cooperating with the gauge member is a cutter case 19, which has cast in one end thereof a pivot pin 20. This pin fits in a hole 21 in one end of the gauge member 4. Around the pivot pin in the cutter case is a spring seat 22, while a similar spring seat is formed in the adjacent part of the gauge member. These two depressions or seats provide space for a spring 23 coiled around the cast-in pivot pin. The ends 24 of this spring 23 are seated in notches in the walls 25 around the seats or depressions.

The gauge member is held on the pivot pin 20 by means of a screw 26 threaded into the end of the pivot pin. Screw 26 has a knurled head 26a by which it may be easily and quickly removed. On one side of the cutter case is a boss 27, which has extending therethrough a hole 28. In this hole is a bushing 29, which has on one end a flange 30 adapted to be engaged by a wrench so that the bushing may be rotated and adjusted in the boss. This bushing is threaded in the hole 28 so that by rotating the bushing its longitudinal position with relation to the boss may be adjusted and held without the use of a screw such as screw 37.

Extending through the bushing and supported therein is a spindle or arbor shaft 31, which has on one end a head 32 adapted to fit within the hole 28 and against one end of the bushing 29. The other end of this spindle or arbor shaft is reduced at 33 to provide a shoulder 34 against which the cutter or cutter blade 36 rests by means of a screw 35. The head 32 has in one edge a grease slot 32a adapted to align with a slot 29a in the bushing for holding a grease for lubricating the shaft.

The bushing 29 may be adjusted by rotation, and after it has once been adjusted it may be locked in adjusted position by means of a screw 37. In order to clean the cutter and remove paper and paste therefrom there is provided a self-adjusting scraper 38, supported in the cutter case and adjacent the cutter by means of a screw 39. This scraper is pivotally supported on the end of the screw adjacent the cutter so that it may adjust itself to the shape and configuration of the cutter blade at this point. It will be observed that this scraper is located adjacent the cutting edge of the blade or cutter.

Extending laterally from the forward end of the gauge member is an arm 40, which has extending rearwardly therefrom a guide pin 41. This pin and the adjacent part of the gauge member provide a guide for the free end of the cutter case and prevent lateral movement of the blade with regard to the gauge member while the cutter or trimmer is in operation or use.

At the forward end of the cutter case is an upper clip or stop member 42, and a lower stop

member 43, which provide space in which a stop pin 44 works for limiting the vertical movement of the cutter blade during operation. This stop pin 44 projects through a hole in the forward end of the gauge member, and is formed on and is part of a spring 45, which has adjacent the pin a loop 46 by which the pin and spring may be manipulated. The part of the spring for supporting and operating the stop pin extends along one side of the gauge member and is supported thereon by means of a loop 47 and a screw 48 passing through the loop into some suitable part of the gauge member. The position of this spring is shown in Figures 4 and 6.

The cutter is circular or disc-shaped, and has extending over it and forming part of the cutter case a flange 49. Formed on the rear part of this flange is a thumb seat 50, while on the front part of the flange is a finger seat 51. In operating or manipulating the trimmer the thumb and one finger are placed in these seats.

It will be understood that I desire to comprehend within my invention such modifications as come within the scope of my claims and my invention.

Having thus fully described my invention, what I claim as new and desire to secure by Letters Patent, is:

1. In a paper trimmer, in combination with a guide, a traveling member on the guide, and means to wipe the guide and apply oil thereto.
2. In a paper trimmer, in combination with a track, a cutter member supported on said track for movement thereon, an attachment on the cutter member adapted to hold the cutter member on the track, and fibrous material on the attachment to wipe the track.
3. In a paper trimmer, in combination with a track, a cutter member mounted on the track for movement thereon, said cutter member having a guide means engaging one side of the track, an attachment on the cutter member engaging the other side of the track and a removable wiper on the attachment engaging beneath the track for cleaning the track.
4. In a paper trimmer, in combination with a track forming a straight edge, a cutter member mounted on the track for movement thereon, means for guiding and holding the cutter member on the track, said means including an attachment engaging one side of the track and extending beneath part thereof, and a removable wiper on the attachment.
5. In a paper trimmer, in combination with a track forming a straight edge, a cutter member mounted on the track for movement thereon, means to guide and hold the cutter member on the track, said means including an attachment engaging one side of the track and extending beneath part of the track, and means on the attachment for wiping and applying a lubricant to the track.
6. A lubricating attachment for paper trimmers consisting of a plate having a lubricant absorbing material thereon, and a supporting bracket extending therefrom.
7. A lubricating attachment for paper trimmers consisting of a plate having on one side a layer of lubricant absorbing material, and a supporting flange extending from one edge.
8. In a paper trimmer, a cutter member having guide means on one side, an attachment on the other side forming a cooperating guide means and a lubricant carrier, and a spring between the

- 5 cutter member and the attachment to resiliently support the attachment on the cutter member.
- 5 9. In a paper trimmer, a cutter member having guide means on one side, a plate mounted on the other side of the cutter member, and a removable cooperating guide and lubricant carrier on said plate. 80
- 10 10. In a paper trimmer, a cutter member having guide means on one side, a plate resiliently mounted on the other side of the cutter member, and a removable cooperating guide and lubricant carrier on said plate. 85
- 15 11. In a paper trimmer, a cutter member having guide means on one side, a plate having a hole in each end, a screw having a head thereon extending through each hole in the plate into the cutter member on the other side of the cutter member, a spring between the cutter member and the plate, and a cooperating guide and lubricant carrier on said plate. 90
- 20 12. In a paper trimmer, a cutter member having guide means on one side, a plate having a hole in each end, a screw having a head thereon extending through each hole in the plate into the cutter member on the other side of the cutter member, a spring between the cutter member and the plate, and a detachable cooperating guide and lubricant carrier on said plate. 95
- 25 13. In a paper trimmer, a gauge member, a cutter case pivoted to the gauge member, a pair of spaced stops on the cutter case, a pin on the gauge member adapted to extend between the stops, and a spring for holding the pin between the stops to limit the swinging of the cutter case on its pivot. 100
- 30 14. In a paper trimmer, a gauge member having at one end a cast-in pivot pin, a cutter case on said pin, a spring on the pivot pin with one end engaging the gauge member and its other end engaging the cutter member, a pair of spaced stops on the cutter case, a pin extending through the gauge member adapted to project between the stops to limit the swinging movement of the cutter case on its pivot, and a spring on the gauge member tending to hold the pin between the stops. 105
- 35 15. In a paper trimmer, a traveling member, a cutter rotatably mounted on said member, a screw adjustably mounted in said member adja- 110
- 40 16. In a trimmer, in combination with a track, a gauge member having on one side a guide for engaging one side of the track and on the other side a yieldingly mounted guide plate adapted to engage the other side of the track, screws extending through the plate into the gauge member for supporting and adjusting the plate, and yielding means between the plate and the gauge member. 115
- 45 17. In a trimmer, in combination with a track, a gauge member having on one side a guide for engaging one side of the track and on the other side a guide plate adapted to engage the other side of the track, holding members for adjustably holding the plate on the gauge member, and yielding means between the plate and the gauge member, said yielding means consisting of a relatively strong spring between two of the holding members and a weaker spring about another holding member. 120
- 50 18. In a trimmer, a traveling member having a boss with a hole therein, a longitudinally adjustable bushing threaded in said hole, and means in the bushing for supporting a cutter. 125
- 55 19. In a trimmer, a gauge member, a cutter case pivoted at one end to one end of the gauge member, a pair of stops at the other end of the cutter case, a pin in the gauge member for guiding the cutter case, a pin adapted to extend through a hole provided therefor in the gauge member between the stops for limiting the movement of the cutter case about its pivot, and a spring for supporting the last-named pin and by which it may be withdrawn from the stops. 130
- 60 20. In a paper trimmer, a rotary cutter having thereon a shaft, a head on the shaft, and a bearing for the shaft to support the cutter, said bearing having a grease slot adjacent the shaft and the head having a grease slot adapted to align with the bearing slot. 135
- 65 21. In a paper trimmer, a traveling member, a cutter rotatably mounted on said member, a screw adjustably mounted on said member adjacent one face of the cutter, and a self-adjusting scraper on the screw adjacent the cutter. 140
- 70 22. In a paper trimmer, a traveling member, a cutter rotatably mounted on said member, a screw adjustably mounted on said member adjacent one face of the cutter, and a self-adjusting scraper on the screw adjacent the cutter. 145
- 75 23. In a paper trimmer, a traveling member, a cutter rotatably mounted on said member, a screw adjustably mounted on said member adjacent one face of the cutter, and a self-adjusting scraper on the screw adjacent the cutter. 150
